UNITED STATES PATENT OFFICE.

PATRICK McDONALD, OF WESTVILLE, ILLINOIS.

CAR COUPLING.

Application filed May 26, 1923. Serial No. 641,788.

To all whom it may concern:

Be it known that I, PATRICK McDONALD, a citizen of the United States, and resident of Westville, in the county of Vermilion and State of Illinois, have invented certain new and useful Improvements in Car Couplings, of which the following is a specification.

This invention relates to car couplings and while not limited thereto relates more particularly to couplings for use on mine cars and other similar cars, such as used on narrow gauge trackways in excavating operations, etc.

One of the objects of this invention is to provide a safe coupling for cars of this class that may be coupled or locked together without the necessity of workmen entering between the cars as is now necessary with the couplings in common use.

Another object is to provide a coupling that will not become engaged or disengaged while the cars are in motion, since its parts must be manually operated before these functions can be performed.

A further object is to provide a semi-rigid coupling which will prevent derailments caused by jerking of the more flexible couplings now in use.

A still further object is to provide a coupling having the novel arrangement, construction and combination of parts hereinafter described and illustrated in the accompanying drawings.

In the drawings, Figure 1 is a plan of the coupling members.

Figure 2 is a sectional side elevation of coupling members.

Figure 3 is an end elevation taken on the line III—III of Figure 2, showing the manually operated mechanism for actuating the draw bar latch.

Referring more particularly to the drawings, the numerals 2 and 3 designate the housing members of my improved coupling, which are adapted to be secured to the under side of two cars A and B, the ends of which are in abutting position.

The housing 2 has a cross bar or web 4 which is provided with a central aperture 4^a for the reception of a draw bar 5. The draw bar 5 is of slightly less diameter than the aperture 4 and passes freely through the same. Due to the diameter of the bar 5 being less than the aperture 4^a, the bar 5 has a limited lateral or swinging movement.

A coupling head 6 is rigidly mounted on

the forward end of the draw bar 5 and is provided with a latch bar 7 adapted to move vertically relative to the head. The bar 7 is provided with a vertically disposed bolt 8 which extends upwardly through the coupling head 6 and has its upper end terminating in an eye 9 which has a link 10 mounted therein. The bolt 8 and link 10 form means to be grasped by the operator to lift the latch bar 7.

A pair of springs 11 and 12 are mounted on the bar 5 adapted to oppose the longitudinal movement of the bar in either direction and thus resiliently cushion the movements of the bar. The spring 11 is mounted between a follower 14 which abuts the rear end of the coupling head 6 and the web 3 and opposes the rearward movement of the bar 5 while the spring 12 is mounted between the web 3 and a follower 15 held in position by a nut 16 screwed on the rear end of the bar 5, and serves to oppose the forward movement of the bar.

A housing 18 is slidably mounted in the draw head 3 and is provided on its forward end with a latching head 19 which has a rearwardly inclined forward face 20. The bar 18 is adapted to be forced under the latch bar 7 when the cars are coupled, and the inclined face 20 of the head 19 serves as a lifting cam to force the bar 7 upwardly, thereby causing it to ride over the head 19.

The draw bar 18 is in the form of a link. That is, it has an elongated central opening or slot 22 therein and a bolt or pin 23 is mounted in the housing 3 and extends through the slot 22 to limit the longitudinal movement of the bar 18. The pin 23 also serves to transmit the pulling stress directly to the housing 3.

The draw bar 18 is adapted to be normally retracted to a position within the housing 3 when uncoupled, and is provided with suitable mechanism for holding it in this position and for forcing it out of the housing to permit it to enter the coupling head 6 on draw bar 5.

The rear end of the draw bar 18 is connected by a link 25 to a crank arm 26 secured to an operating shaft 27 journaled in bearings 28 secured on the bottom of the car B. Suitable hand cranks 29 are secured on the opposite ends of the shaft 27 to permit manual rotation thereof, and rotation of the shaft 27 will serve to reciprocate the draw bar 18 longitudinally of the housing 3.

A coil spring 30 is mounted on the shaft 27 and has one end secured to the shaft and its other end secured to the adjacent bearing 28 so that rotation of the shaft in a clockwise direction to move the draw bar out of the housing 3, into a coupling position, will serve to tension the spring 30, thus causing sufficient tension on the spring to cause the shaft 27 to automatically return to its normal position when the crank handles 29 are released, unless the draw bar latch head 19 is engaged with the latch bar 7.

Assuming that it is desired to couple the two cars A and B, one of the crank handles 29 will be grasped by the operator and the shaft 27 rotated clockwise to force the draw bar 18 out of the housing 3. The cars will then be moved toward each other until the latch head 19 of the bar 18 is forced under the latch bar 7 in coupling head 6, which latch bar will automatically fall into locking position and prevent withdrawal of the draw bar 18.

When it is desired to uncouple the cars 25 the operator will grasp the link 10 secured to the bolt 8 of the latch bar 7 and lift the latch bar. As soon as the latch bar is lifted sufficiently to clear the latch head 19, the spring 30 on the shaft 27 will cause the 30 shaft to rotate counter-clockwise and thus withdraw the draw bar 18 to its normal position within the housing 3.

While I have shown and described only 35 one specific embodiment of my invention it will be understood that I do not wish to be limited thereto since various modifications may be made without departing from the

scope of my invention as defined in the appended claim.

I claim:—

A coupler comprising a housing, a draw bar mounted in said housing and adapted to move longitudinally thereof, said draw bar being provided with a longitudinal slot, a rigid pin secured in said housing and passing through said slot and adapted to cooperate with said slot to limit the movement of said draw bar, an operating shaft connected to said draw bar by suitable crank and link mechanism, so that rotation of said shaft will move said draw bar longitudinally relative to said housing, fixed bearings for said shaft, a coil spring mounted on said shaft and having its one end secured to said shaft and its other end secured to one of said fixed bearings, so that rotation of said shaft to move said draw bar out of said housing into coupling position will tension said spring sufficiently to cause an automatic return of said draw bar and shaft when said draw bar is released from coupling position, and an upwardly projecting latching head on the forward end of said draw bar, said latching head having a downwardly inclined or beveled forward face so as to cause said head to be forced under and to automatically engage with the latch bar of a mating coupler when said draw bar is moved forward so as to project beyond the forward end of its housing.

In testimony whereof, I have hereunto signed my name.

PATRICK McDONALD.
